UNITED STATES PATENT OFFICE.

ALEXIS LE BLANC, OF BROOKLYN, NEW YORK.

BRAIDING-MACHINE.

No. 875,190.

Specification of Letters Patent.

Patented Dec. 31, 1907.

Application filed January 20, 1906. Serial No. 296,933.

To all whom it may concern:

Be it known that I, ALEXIS LE BLANC, a citizen of the United States, residing in Brooklyn, in the county of Kings and State 5 of New York, have invented certain new and useful Improvements in Braiding-Machines, of which the following is a specification.

The present invention relates to improvements in braiding machines, and more particularly to such machines wherein the threads from one set of bobbins are caused to orbitally rotate in a reverse direction to the threads from another set of bobbins, and these to alternately occupy elevated and depressed positions whereby the threads may 10 pass and be braided together.

An object of the invention is to provide means whereby each set of bobbins may travel in a regular circular orbit and the 15 threads from the bobbins of one set be raised and lowered to alternately pass over and under the bobbins and the threads from the other set of bobbins.

In the drawings accompanying and forming a part of this specification, Figure 1 represents a vertical central section of a practicable embodiment of a form of my invention. Fig. 2 illustrates in perspective an arm and its bracket for raising and lowering 20 the thread from one of the bobbins. Fig. 3 is a plan view of the device illustrated in Fig. 1, a portion of the gear-track plate being broken away. Fig. 4 shows in perspective one of the carriers for the upper set of bobbins. Fig. 5 illustrates in perspective one of the rotary devices for forwarding the bobbin carriers. Fig. 6 is a side elevation of the device shown in Fig. 1, the parts being in substantially the same position; and Fig. 7 25 is a diagrammatic representation of various positions of the lower bobbin thread, the bobbin carrier forwarding device, the bobbin carriers, and the bobbin carriage, which diagram will be described in detail in the following description of the machine and its operation.

The mechanism herein illustrated embodies a base portion designated by 20, which in the present instance is shown as 30 having an integral arm 21 which curves up over the various mechanism and at its center portion carries a tubular guide 22, which may carry at its lower end an anti-friction

eye 23, which will in the present embodiment be the braiding point of the machine. This, 55 as many of the other details of construction, may of course be altered as occasion may demand without departing from the scope of my invention. The frame is shown as carrying a pair of journal bearings 24 in which is 60 mounted the driving shaft 25, which is shown as carrying a pair of fast and loose pulleys 26, 27. The driving shaft is shown as carrying a bevel pinion 28 which meshes at its lower side with a bevel gear 29 fast upon a 65 sleeve 30, which sleeve is journaled upon a stationary upstanding spindle 31, which spindle is shown as hollow and as having a flange portion 32 bolted to the base 20, and which flange forms a bearing upon which the 70 portion 290 of the gear wheel 29 is stepped, a suitable ring 33 may be carried by the flange 32 and surround the portion 290 of the gear-wheel for retaining lubricant.

The upper portion of the pinion 28 is in 75 mesh with a bevel gear 35 supported by a collar 350 on the sleeve 30 and having a hub 36 which surrounds the sleeve 30, and to a flange 360 of which hub is bolted a framework 80 construction, which in the present description will be called a "bobbin carriage" since it supports both sets of bobbins, carrying with it one set and guiding and sustaining the weight of the other set, it comprising a plate 37 having upwardly projecting side 85 portions 38 which are recessed, as at 39, at given intervals to afford passages for the threads where these are raised and lowered. Depending from the bobbin carriage are shown a number of brackets 40 for carrying 90 the lower bobbins, designated herein by 41, the carrying means being some suitable contrivance, as for instance a spindle 42 and some means, as for instance a cotter pin to hold the bobbin from running off the spindle, 95 the bracket may also have an arm 43 provided with a suitable thread guiding aperture through which the thread may be passed. Upon the bobbin carriage the upper bobbins are carried by some suitable bobbin carriers, 100 see more particularly Fig. 4, wherein there is shown a body portion 45 having a channel 46 in its lower portion and a downwardly projecting flange 47, which flange is received in a guideway 48 and the channel 46 receives a 105 rail, as it were, 49 of the bobbin carriage.

Segmental plates 450 engage the upper faces of the body portion 45 and hold the bobbin carriers to their track or guideway.

The bobbin carrier is shown as provided

5 with a pair of arms 50 having suitable recesses 51 for receiving the spindle 52 of an upper bobbin. Each carrier is also provided with a tension arm 53, it having some anti-friction eye as 54 through which the thread

10 will pass after passing through some suitable tension device as 55. The employment herein in connection with the bobbins and the threads delivered therefrom of the terms "upper" and "lower" is arbitrary, and such

15 terms are adopted for convenience of description only, they being suggested by the relative positions of the sets of bobbins in the present illustration. The present illustration also arbitrarily shows eight upper bobbins and eight lower bobbins.

The frame of the machine is shown as carrying a cam device 60, it being supported upon a bracket 61 at one side of the machine frame and by a suitable upright 62. The cam frame is shown as of a shelving disposition and having a cam groove or runway in it embodying upper and lower faces 63, 64 respectively in which the runway follows a sinuous path embodying a number of upwardly and a number of downwardly projecting cam faces, in the main constituting eight upward faces and eight downward faces; that is so that the roll 70 upon the thread carrying arm 71 pivoted to a bracket 72 suitably secured to the bobbin carrier and rotating therewith will, when traversing the runway, make eight elevations and eight descents during its traverse of this groove and during each rotation of the bobbin carriage will make eight elevations and eight descents thus passing the thread which it controls between the upper bobbin carriers sixteen times. The thread is shown as passing from the thread guide of the arm 43 through a tension device 73 and guides 74, 75, the latter guide being a hole bored through the pivot of the arm 71 and from thence through an eye 76, which may be provided with some anti-friction device.

The sleeve 30 has fast with it a spider 80 carrying a number of rotary bobbin carrier forwarding devices 81, see more particularly Fig. 5, each of which comprises a shaft portion 82 supported by bearings 83 in the spider, and are shown as having cup shaped carrier forwarding ends 84; each of these in the present instance having a cylindrical rim or edge 85 for engaging grooves 86 in the contiguous ends of the bobbin carriers, see more particularly Figs. 3 and 4. Each of these forwarding devices has a by-pass for the thread, in the present instance the cup shaped end has a segmental opening 87 for the passage of the thread through it; the other end

of the shaft 82 is provided with a bevel pinion 88 which is in mesh with a bevel gear track 89 carried by a plate 90, which in the present instance is held from rotation by being fast with the spindle 31, the ratio of the gears in this instance being 16 to 1. The bobbin carriers are supported on the rotary bobbin carriage and are given a revolution in a reversed orbit by the forwarding devices, such devices do not in the present illustration bear the weight of the bobbin carriers with the exception of steadyng these. In some instances the connection between the carriers and the carriage may be loose enough to give free movement involving a minimum of friction. 65 70 75 80 85 90

In starting the operation the threads from all the bobbins may be brought indiscriminately to the braiding point. The contour of the cam track between the faces 63, 64 is such that all the arms 71 will rise and fall in unison, and their rising and falling will be so timed to the rotation of the members 84 that they will pass through the segmental opening 87 and thus be enabled to alternately pass over and under the upper set of bobbins and bobbin threads, thereby braiding their threads together. 85 90

By referring more particularly to Fig. 4 it will be seen that the slots 86, the walls of which constitute the forwarder engaging faces, are transversely disposed to the portion of the carrier which lies between the plates 45 and the track forming edge of the member 38, and that these forwarder engaging faces have portions disposed in the plane 100 of the track and by this means the forwarders will exert their influence or pressure in a line or path coincident to the path in which these forwarders engage the track, and by this means there will be no cramping or binding of the carriers upon the track. The forwarders or drivers, designated in a general way by 81, are so constituted that they will engage the front and back ends respectively of adjacent carriers and at certain intervals 110 open segments 87 will be so presented that the thread may be passed through such segment of the forwarder and between the carriers. And this opening of a cut away or by-pass between the carriers permits the thread 115 to be passed through such by-pass, that is, between the carriers and through the opening in the forwarder at the time that the thread is being given its fastest movement, for it must be remembered that the levers 120 being vibratory must come to a complete rest at each end of their stroke and that the intermediate portion of the movement will consequently be the fastest, and it is during this fast thread movement that the thread 125 is passed through this by-pass.

In the diagram Fig. 7 the arrow *a* indicates the direction of movement of the bobbin car.

riage, and the arrow *b* indicates the direction of movement of spider 80 and of the upper set of bobbins. In such diagram the thread is designated by 100 and is the thread drawn from one of the lower bobbins, the other parts, so far as they need to be designated by reference characters are designated by the reference characters which these parts have in the other figures of the drawings. The 10 positions indicated by the reference characters 1 to 5 inclusive are those successively assumed by the parts in moving what might be called half a pitch distance, that is half of the angular movement necessary to bring one 15 of the bobbins to the position which was at the inauguration of its movement occupied by the preceding bobbin, in the present instance there being eight bobbins their centers will be substantially forty-five degrees 20 apart, and the amount of movement from the positions 1 to 5 will represent a movement of one bobbin and of one of the forwarding devices 84 through an angular distance of twenty-two and a half degrees, being one 25 sixteenth part of a circle. In the first position the thread 100 at the left hand side is assumed to be going down into the opening 87 of the forwarding device and into the passage 39 in the bobbin carriage framework. 30 In position the thread has passed out of such opening 87 and is moving with the bobbin carriage, and also down further into the passage 39. In the position illustrated in the third position the thread is at the lowermost 35 portion of its downward movement, and as indicated by the arrow adjacent thereto is about to rise. In the fourth position it has commenced to rise and is at such position that the next step in advance will reseat it in 40 the opening 87, the thread in the movement from the first to the fifth position having passed under one of the upper bobbins, and the thread passing from such bobbin to the braiding point. The thread will successively 45 assume the position relatively to the bobbin carriage and the passage 39 represented in the sixth to the ninth position, which ninth position is the same as the first position. From the line A—B to the line E 50 may be assumed to be what is above referred to as a pitch distance or the distance of one-eighth of a rotation, and to the line C—D as half a pitch distance. The space between the lines A—B and E has been divided off 55 for convenience into eight equal portions, and the various relative positions of the thread, the forwarding device and the bobbin carriage are illustrated in positions five and ten to thirteen inclusive, representing 60 the positions occupied during the time the bobbin carriage travels from the line A to the first line to the right thereof. The angular advance of the forwarding device 84 from the position five to the position thirteen will

be about three degrees. The threads are 65 crossed sixteen times to each rotation of the bobbin carriage.

It will be seen that each of the bobbin carriers is engaged at each end by the flange 85 during more than half of the time, and that 70 each carrier is always engaged by one of these forwarding devices; sometimes it is being pushed and pulled at the same time, and sometimes it is being pushed, and sometimes it is being pulled. When one forwarding device is to release its hold on one of the bobbin carriers the forwarding device at the other end of such carrier has obtained a secure hold and the release and reengagement is carried on without affecting the steady advance of 75 80 the bobbin carriers.

It will be seen that the cam device or structure 60 embodies in the present form of construction two members 600 and 601, these being rigidly connected in the present instance by integral strap members 602 which are cast on one of the members 600 and 601. These strap members are shown as bowing outwardly to clear the rolls 70 in their passage around the cam member. It has been 90 found that in rapidly running the machine it is necessary to have the cam face 63 for positively returning the arms to their lower position after they have been raised, since to rely upon spring means for returning the 95 arms the rolls 70 will jump from one cam elevation to the next and will not get to the bottom of the drop face. Such improper movement if permitted would not only prevent the proper braiding and passing of the 100 threads; but would also at times break the arms.

Having described my invention I claim:

1. In a braiding machine, the combination with a rotary bobbin carriage, means fast 105 therewith for supporting and orbitally moving a series of bobbins, said carriage having a bobbin carrier track, a series of bobbin carriers supportedly mounted upon said track, each of said carriers having two sets of forwarder engaging faces, a series of forwarders each for engaging a set of said faces on two adjacent carriers, and having a by-pass for threads, means for actuating said forwarders for opening the by-pass between the carriers 110 at predetermined intervals, and means for passing the threads of one series of bobbins through said by-passes when opened.

2. In a braiding machine, the combination with a rotary bobbin carriage, means fast 120 therewith for supporting and orbitally moving a series of bobbins, said carriage having a bobbin carrier track, a series of bobbin carriers supportedly mounted upon said track, each of said carriers having two sets of forwarder engaging faces, a series of forwarders each for engaging a set of said faces on two adjacent carriers, and having a by-pass for 125

- threads, means for actuating said forwarders for opening the by-pass between the carriers at predetermined intervals, vibratory arms and means for moving these with accelerated speed between the dead centers in proper timing for passing the threads from one series of bobbins through said by-pass at the accelerated portion of its movement for alternately bringing the threads from the respective series of bobbins at the outer side of the threads of the other series, and passing the threads through said by-pass at its accelerated movement.
3. In a braiding machine, the combination with a rotary bobbin carriage, means fast therewith for supporting and orbitally moving a series of bobbins, said carriage having a bobbin carrier track, a series of bobbin carriers supportedly mounted upon said track, each of said carriers having two sets of forwarder engaging faces, a series of forwarders each for engaging a set of said faces on two adjacent carriers and comprising a rotary member having a recess constituting a thread by-pass, means for revolving said forwarders, for revolving the carriers, means for rotating the forwarders for opening the by-pass between the carriers, and means for passing the threads from one series of bobbins through said by-pass when opened alternately in opposite directions.
4. In a braiding machine, the combination with means for orbitally moving a series of bobbins, means for supporting carriers for a second series of bobbins, each carrier having driver engaging faces, a series of rotary orbitally movable bobbin carrier drivers each embodying an annular member for engaging said driver engaging faces on adjacent carriers and each having an open segment constituting a thread by-pass of sufficient width to effect the release of the engagement of the driver with the engaging faces on each carrier once during each rotation of said driver, vibratory arms revoluble with the first series of bobbins and means for vibrating these in proper timing with the presentation of the open segments of the drivers upwardly and downwardly respectively, the arms moving the thread down during the period of the downward movement of the open segments and moving the thread up during the upward movement of said open segments.
5. In a braiding machine, the combination with a rotary bobbin carriage embodying means for orbitally moving a series of bobbins, a series of bobbin carriers supported on said carriage for carrying a second series of bobbins, a rotary spider concentrically disposed relative to said carriage, means for rotating said carriage and spider in opposite directions, each of said carriers being provided at its ends with driver engaging faces, a series of shafts mounted upon said spider, each carrying at one end a bevel pinion and at its opposite end an annular member for engaging said driven engaging faces on the adjacent ends of two of said carriers, and each having an open segment constituting a thread by-pass between the carriers of sufficient width to effect the release of the engagement of the driver with the engaging faces on each of the carriers once during each rotation of said driver, arms pivoted to the bobbin carriage and having eyes for the passage of the thread from the first series of bobbins, a cam frame disposed adjacent to said arms and having a pair of cam faces for engaging said arms for positively raising and lowering these for passing the threads guided thereby through the open segments of the carrier drivers, and a stationary gear track for said pinions.
6. In a braiding machine, the combination with a framework embodying an annular flange, said framework constituting a bobbin carriage and it having means for supporting and carrying a series of bobbins, and said flange being provided with a recess to accommodate the raising and lowering of the threads from said bobbins, a series of arms pivoted to said flange and each having guiding means, said arms being for raising and lowering said bobbin threads through said flange passages, said flange being provided with a guideway, a series of bobbin carriers for a second series of bobbins supported on said guideway and each of these provided at its ends with driver engaging faces, a spider disposed concentric to said carriage, means for rotating the spider and carriage in opposite directions, a series of shafts radially supported by said spider and each of these provided with a pinion, a stationarily disposed gear track for said pinions, each of said shafts carrying an annular flange for engaging said driver engaging faces and adapted for engaging the faces on the adjacent ends of two of the carriers, each of said flanges having an open segment, a stationarily disposed flange member surrounding said carriage and having a sinuous runway, rolls carried by said pivoted arms for traversing said runway, the timing of the movement of the open segments of said drivers at the passages in the flange of the carriage and the disposition of the sinuosities of said track being such that at each time the arms pass the threads downwardly the open segments will pass downwardly, and each time the arms pass the thread upwardly the segments will pass upwardly, the segments at such time being presented at the open passages in the flange of the carriage.
7. In a braiding machine, the combination with a track, of a series of bobbin carriers mounted for orbital movement on the track and each having forwarder engaging slots at each end disposed transversely of the plane

of engagement with said track, forwarders for engaging said faces; means for orbitally moving said forwarders for applying forward movement to said carriers and exerting their force in the said plane of the said track, the forwarders being provided with thread passage interruptions in their engaging faces, means for actuating these for operating a thread passageway at predetermined inter-

vals, and means for passing the threads 10 through said passageways at such intervals.

Signed at 9-15 Murray street, New York, N. Y., this 18th day of January, 1906.
